FLUID FUEL BURNER OR SIMILAR ARTICLE

Reginald W. Beckett, Elyria, Ohio

Application March 21, 1950, Serial No. 8,667

Term of patent 14 years

(Cl. D81—2)

To all whom it may concern:

Be it known that I, Reginald W. Beckett, a citizen of the Dominion of Canada, residing at Elyria, in the county of Lorain and State of Ohio, have invented a new, original, and ornamental Design for a Fluid Fuel Burner or Similar Article, of which the following is a specification, reference being had to the accompanying drawings, forming a part thereof, in which:

Figure 1 is a front perspective view of a fluid fuel burner, showing my new design;

Fig. 2 is a rear perspective view of the burner shown in Fig. 1;

Fig. 3 is a front elevational view of the burner shown in the preceding figures; and

Fig. 4 is a top plan view of the burner shown in the preceding figures.

The characteristic features of my design reside in the portions of the drawings shown in solid lines.

I claim:

The ornamental design for a fluid fuel burner or similar article, substantially as shown and described.

REGINALD W. BECKETT.
